UNITED STATES PATENT OFFICE.

GILBERT C. BELL, OF AUGUSTA, GEORGIA.

REFRIGERATOR AND DISPENSER.

Application filed May 5, 1925. Serial No. 28,207.

My invention is a combined refrigerator and dispenser which is particularly well adapted for the reception of bottled liquid commodities, and it consists in the combinations, constructions and arrangements herein described and claimed.

An object of the invention is the provision of a device of the character described which affords facilities for holding a plurality of articles, such as bottles of liquid commodities, in position to be affected by a refrigerant within the device and so that the articles can be removed from the device without air from the space outside of the device gaining entrance thereto.

A further object of the invention is the provision in a device of the character described of a delivery chamber in open communication with a cooling space within the device and from which an article can be removed without communication being established between the cooling space and the space surrounding the device.

A further object of the invention is the provision of a device of the character described having a delivery chamber in open communication with a cooling space within the device and means within the cooling space for causing guided movement of a series of bottles or like articles so that the outermost article of the series will be moved to position in the delivery chamber to be removed from the latter.

Other objects and advantages will be apparent from the following description, considered in conjunction with the accompanying drawings, in which

Figure 1 is a perspective view of a combined refrigerator and dispenser embodying the invention.

Figure 2 is a section along the line 2—2 of Figure 1.

Figure 3 is a section along the line 3—3 of Figure 2.

Figure 4 is a section along the line 4—4 of Figure 2.

A device embodying the invention comprises a case having a bottom 1, parallel front and rear walls 2 and 3 respectively, parallel side walls 4 and a top or lid 5 which may be hinged at 6 to the rear wall 3. The

walls of the case may be formed of any suitable known material and may include layers of heat insulating material, as at 7. The meeting portions of adjacent walls of the case may be secured together in any suitable known manner so as to provide fluid tight joints therebetween.

The case may be supported on legs 8 so that the bottom 1 will be substantially horizontal.

The bottom 1 extends beyond the front face of the front wall 2 in the form of a shelf 9 which is provided with an upstanding marginal flange 10 having fluid tight connection at its ends with the front wall of the case so that any liquid falling upon the shelf 9 will be retained between the flange 10 and the front wall of the case for drainage through a drain pipe 11 which has the open upper end portion thereof in communication with a drain opening 12 in the shelf. The drain pipe 11 may extend to any desirable place.

The front wall 2 is shown as being provided with a plurality of spaced apart outlet openings 13, each of which preferably is rectangular in configuration and terminates at its lower end substantially flush with the upper face of the bottom 1 and at its upper end below the level of the upper end of the front wall 2. An article supporting and guiding frame is provided for each of the outlet openings 13 and extends within the case on the bottom 1 from the inner end of the outlet opening with which it is associated to the rear wall 3 of the case. Each article supporting and guiding frame comprises a bottom 14 which rests flatwise on the bottom 1 and may be secured to the latter in any suitable known manner, if desired. Each supporting and guiding frame also comprises a pair of vertical side members 15 which are upstanding from the longitudinal edges of the bottoms 14 and are coextensive in length with the latter being joined at their front edges to the front wall 2 of the case at the side edges of the particular outlet opening 13 with which they are associated and being secured at their rear edges to the rear wall 3 in any suitable known manner. The side walls 15 of each supporting and

- guiding frame terminate at their upper ends at a level considerably below that of the upper end of the space within the case. The respective side members 15 of each supporting and guiding member are formed with horizontally aligned guide slots 16, which extend longitudinally of the side members from the forward ends thereof for part of the length of such side members. The guide slots 16 are provided with outwardly extending flanges 17 and 18 at their upper and lower edges respectively to provide bearing surfaces of relatively great area for the oppositely extending lateral slide lugs 19 of a pusher block 20 which is slideable longitudinally of the supporting and guiding frame in which it is disposed in sliding contact with the side members 15 and to and from position to be projected through the outlet opening 13 at the outer end of that particular supporting and guiding frame. The slide lugs 19 of each block 20 are provided with laterally offset rearwardly extending rigid attaching arms 21 having laterally turned rear end portions 22 to which the rearward ends of springs 23 are attached. The respective tension springs 23 are disposed at opposite sides of the particular guiding and supporting frame with which they are associated and are attached at their forward ends to attaching lugs or ears 24 which extend rearwardly from the front wall 2 of the case at opposite sides of the outlet opening 13 with which they are associated. The tension springs 23 which are connected through the rigid arms 21 with each slide block 20 act to urge that slide block continuously in its supporting and guiding frame to position to extend through the outlet opening 13 at the outer end of that guiding and supporting frame as shown at the left hand side of Figure 2. Each pusher block 20 has the front face thereof curved concavely in cross sectional contour as indicated at 25 to closely contact with the rear bottle of a series of bottles 26 in the supporting and guiding frame. The respective bottles will be disposed upright in sliding contact at their lower ends with the bottom of the supporting and guiding frame in which they are disposed. The action of the springs 23 on the pusher block within each supporting and guiding frame will cause forward movement of the series of bottles in that frame so that the foremost or outer bottles of the series will be forced through the outlet opening at the end of the supporting and guiding frame to a delivery chamber 26 at the outer end of the outlet opening 13. Each delivery chamber 26 has a pair of side walls 27 upstanding from the shelf 9 and being merged at their inner ends into the front wall 2 at opposite sides of the outlet opening 13 with which that particular delivery chamber is associated, the side walls 27 being merged one into the other at their outer ends by a front wall 28 which is shown as being arcuately curved in cross sectional contour. The vertical walls 27-28-27 of each delivery chamber have a fluid tight fit or connection at their lower ends with the shelf 9 and extend above the level of the upper end of the outlet opening 13 with which they are associated, the delivery chamber therewithin being covered at its upper end by a lid or cover 29 that is hingedly attached at 30 to the front wall 2 of the case. The walls 15 of each supporting and guiding frame are formed with perforations 31. The space within the case is adapted to hold a suitable refrigerant which may be brine or may be ice and the liquid resulting from the melting of the ice. It will be observed that a relatively wide space is provided midway of the side walls 4 between adjacent supporting and guiding frames to accommodate a relatively large block or piece of ice which may be lowered to position to rest on the bottom 1 when the lid 5 of the case has been raised. A tubular conduit 32 has an end portion thereof fitting within an opening in one of the side walls 4 so that the conduit 32 is in open communication with the space within the case at a level slightly above that of the upper ends of the outlet openings 13. The space within the case therefore is adapted to hold a liquid refrigerant to a level slightly above that of the upper end of the outlet opening 13 and the excess liquid then will pass into the conduit 32 and will be discharged from the latter through a liquid sealing cup 32' onto the drain shelf 9, whence the discharged liquid will pass through the drainage opening 12 and drain pipe 11 to any suitable place. Each delivery chamber 26 thus will be filled with liquid from the cooling space within the case to a level above the upper end of the outlet opening 13 which establishes communication between that delivery chamber and the space within the case when the level of liquid within the case is above the level of the upper end of the outlet opening, as at 33 in Figure 3. A liquid seal thus is established between the cooling space within the case and the space outside of the case above the level of the liquid in the delivery chambers. An article lifting frame is provided for each of the delivery chambers 26 and is movable vertically in the latter when the lid 29 thereof has been raised to lift a bottle or like article above the level of the liquid in the delivery chamber so that the bottle or like article can be conveniently grasped and removed from the delivery chamber. The lifter now preferred by me is formed of wire and has a bottom member 34 adapted to rest upon the bottom of the delivery

chamber and onto which the outermost bottle or like article of a series will be deposited as a result of the action of the pusher block 20 in the supporting and guiding frame in which said bottle was placed. The lifter has a handle 35 which is of inverted U-shape and is vertically disposed, the ends of the handle being secured to the bottom 34 at diametrically opposite points on the latter so that the side members of the handle will extend vertically at opposite sides of the bottle that is resting on the bottom 34 above the level of the upper end of the bottle. The side members of the handle 35 are stayed to each other by an outwardly curved horizontal brace member 36 which extends laterally outward from the side members of the handle or in other words away from the outlet opening 13 with which the lifter is associated, whereby the horizontal staying member 36 will engage with the bottle on the bottom 34 intermediate the height of the bottle and tend to prevent accidental displacement of the bottle from the lifter. Each delivery chamber, preferably is provided with stop members, not shown, for limiting the upward movement of the lifter therewith so that the lifter cannot be completely removed from the delivery chamber.

A drain cock 37 is in communication with the cooling space within the case at the lower end of the latter.

A removable tray 38 may be supported within the case above the level of the refrigerant therewithin, as for example on supporting strips 39 which are secured to certain of the vertical walls of the case in any suitable known manner. The tray 38 of course is adapted to support various articles, such as food stuffs, within the case.

From the foregoing description of the various parts of the device, the operation thereof may be readily understood. A series of articles, such as the bottles B is placed in each of the supporting and guiding frames and the outermost article of the series will be moved automatically to position on the lifter within the delivery chamber at the outer end of the supporting and guiding frame on which that particular series of articles is supported. The level of the refrigerant within the cooling space within the case will be maintained above the level of the upper end of the outlet openings 13 and below the level of the upper end of the delivery chambers because of the position of the upper end of the conduit 32 which as hereinbefore pointed out is in open communication with the cooling space within the case. Therefore, the article within the delivery chamber can be removed therefrom by manipulation of the lifter which is within that delivery chamber without any relatively warm air from the space outside of

the case being admitted to the cooling chamber. As the outermost article of each series is removed from the delivery chamber, the next article of the series will be moved outwardly through the outlet opening 13 into the delivery chamber, but this movement of the next article to position into the delivery chamber cannot be effected until the lifter for that delivery chamber has been lowered until the bottom portion of the lifter is positioned below the lower end of the article that is to be moved into the delivery chamber. Any liquid dripping from the bottle will fall upon the drainage shelf 9 and thence will pass through the drain opening 12.

I claim:—

1. A device of the character described comprising a case having a lateral outlet opening, a delivery chamber at the outer end of the outlet opening in open communication with the latter, said delivery chamber extending above the level of the upper end of the outlet opening and said delivery chamber and said case being adapted to hold a liquid refrigerant to a level above that of the upper end of said outlet opening, a supporting and guiding frame extending within the case from the inner end of the outlet opening, said frame comprising a bottom member and a pair of spaced apart upstanding side members between which a series of articles can move to position to pass one at a time through said outlet opening, said side members being apertured, a drainage shelf at the lower end of said delivery chamber, said drainage shelf having an upstanding marginal flange and a drain opening.

2. A device of the character described comprising a case having a lateral outlet opening, a delivery chamber at the outer end of the outlet opening, said delivery chamber and said casing being adapted to hold a liquid to a level above that of the upper end of the outlet opening, means within the case to receive articles one at a time through the outlet opening into the delivery chamber, and a tubular conduit having the upper end thereof in communication with the space within the case above the level of the upper end of the outlet opening and below the level of the upper end of the delivery chamber.

3. In a device of the character described, an article supporting and guiding frame comprising a horizontal bottom member on which a series of upright substantially cylindrical articles can be placed, a pair of upstanding side members at the edges of said bottom member for preventing appreciable lateral movement of said articles, said side members having longitudinally extending horizontally aligned slots, a pusher block movable longitudinally of said

supporting and guiding frame between the side members of said frame, said pusher block having oppositely extending lateral slide lugs extending through said slots, said 5 pusher blocks having its face that is next to said articles concavely curved transversely of the block to conform to the curva- ture of the adjacent article, and tension springs connected with said lugs and tending to urge said pusher block along said 10 supporting and guiding frame against said series of articles.
